UNITED STATES PATENT OFFICE

2,054,323

REFRIGERATING APPARATUS

William C. Holbrook, Dayton, Ohio, assignor, by
mesne assignments, to General Motors Corpora-
tion, a corporation of Delaware

Application January 31, 1928, Serial No. 250,808
Renewed March 4, 1935

2 Claims. (Cl. 220—9)

This invention relates to refrigerators and more particularly to a cabinet made of molded material.

An object of this invention is to provide a refrigerator which does not corrode or warp.

Another object of this invention is to provide a refrigerator made of molded material and which has great structural strength.

Another object of this invention is to provide 10 a method of making a refrigerator of non-corrodible construction.

Another object of this invention is to provide a method which reduces the cost of manufacture of a refrigerator.

15 Another object of this invention is to provide a refrigerator made of materials so selected and placed that corrosion is prevented and great structural strength is obtained.

Further objects and advantages of the present 20 invention will be apparent from the following description, reference being had to the accompanying drawings, wherein a preferred form of the present invention is clearly shown.

In the drawings:

25 Fig. 1 is a vertical cross-sectional view showing a refrigerator embodying my invention;

Fig. 2 is a horizontal cross-sectional view along the line 2—2 of Fig. 1 with the refrigerator mechanism omitted;

30 Fig. 3 is an enlarged detailed view of the construction around the door jamb shown in Fig. 2;

Fig. 4 is a perspective view of a frame which may be used in the construction of a refrigerator embodying my invention;

35 Fig. 5 is a horizontal cross-sectional view similar to Fig. 2 but showing a modified construction, and

40 Fig. 6 is a vertical cross-sectional view, with parts broken away, of a machine for practicing a step in my method of manufacturing refrigerators.

A refrigerator embodying my invention is generally designated as 20 and comprises an outer shell 21, an inner lining 22, a frame 23 and insulation 24.

45 The frame 23 may be made of angle metal members such as sheet metal bent to form angle members and, in the embodiment shown in Fig. 4 the frame 23 may comprise struts 26 spacing 50 rectangular bands 27. The bands 27 may be placed in mirror symmetry and the corners may be bridged by struts 26. The front of the frame may have an additional horizontal member 21a adapted to form part of the bottom of the door 55 opening of the refrigerator. A door jamb 28

may be made of some insulating material such as wood and this door jamb may be secured as by screws 29 to the framework 23, preferably within the angles of some of the angle metal members as shown in the drawings. The joint 5 between the angle metal members may be secured by welding, such as by spot welding, diagrammatically indicated at 30. If necessary, the corners may be braced in any suitable manner, such as by gussets placed at the corners, not shown 10 in the drawings.

The outer shell 21 made of molded material may be secured to the frame 23, and one method of securing the shell 21 may be by molding the material directly on the frame in a manner more 15 fully to be described. The outer shell may comprise front wall 31, side walls 32, top 33 and back wall 34. If convenient, part of the outer shell need not be made of molded material, and in Fig. 5, I have shown the back wall 34' made of sheet 20 metal, which metal wall 34' may be secured to the outer shell 21 or to the frame 23 in any suitable manner. If desired, corner metal protecting strips 31', shown in dotted outline in Fig. 3, may be placed on any of the corners embedded in the 25 molded material.

The inner lining 22 which may be of sheet metal may be porcelain lined. It may comprise an open ended box having bottom wall 35, back wall 36, side walls 37 and top wall 38. This lining 22 may be secured at its edges to the framework 23, and preferably to the door jamb 28 by any means such as by screws 39. A finishing strip 40 of molded material may be placed over the door jamb 28 in order to enhance the appearance 35 of the cabinet and to prevent the exposure of wood to the atmosphere.

Between the outer shell 21 and the inner shell or lining 22 there may be placed insulation 24. This insulation may be placed in the space between the shells in any suitable manner. A method of placing the insulation therein may be by sealing the space between the shells by a bottom plate member 41 joining the back wall 34 and the side walls 32 and part of the front wall 31 of the outer shell 21, in order to form a complete enclosure for the space between the shells 21 and 22. An aperture 42 may be provided in the outer shell 21 and insulation in plastic form may be forced into the space by any suitable pumping means and preferably by pumping means of the cylinder and plunger construction.

In practicing the method wherein the outer shell 21 is to be molded directly on the frame 23, 55

a machine such as that shown in Fig. 6 may be used for this purpose. The machine or press may comprise a plunger 50 reciprocated in a cylinder 51 by any powerful means, such as a hydraulic press 52. The cylinder 51 may have connected thereto one or more cabinet molds 53. The mold 53 may have a contour similar to the outside of the refrigerator. Within this mold 53, may reciprocate a core 54 having an outer contour somewhat similar to the interior of the outside shell 21. The cylinder 51 may have placed therein a suitable material 55 for forming the outside shell of the refrigerator, which material may be in the necessary plastic condition. The material 55 may be raised to the necessary temperature to obtain a plastic condition, or if an apparatus powerful enough is used, the material 55 may be used at room temperature. Upon the downward movement of the plunger 50 the material 55 is forced through one or more orifices 56, connecting cylinder 51 and mold 53, into the space between the mold 53 and the core 54. Plungers 57 and 58 having horizontal reciprocation may be provided to abut against the core 54 to form the door opening and any other desired opening, such as the opening 60 for the insertion of the refrigerating machinery. After the plunger 50 has moved downwardly a sufficient distance to displace enough material 55 to form the shell 21, the plungers 57 and 58 are withdrawn horizontally, and then upon further movement of the plunger 50 the plate 61 is forced downwardly to carry with it the core 54. When the core 54 is withdrawn, it carries with it the molded shell 21 below the opening of the mold 53 formed by the plate 62. Bolt-like members 63 then stop further downward movement of stripper plate 61. A further downward movement may be caused in the core-supporting table 64 to which the core 54 is attached by any means, such as screws 65. This further downward movement of the core 54 withdraws the core from the shell 21, which shell is prevented from moving downward by the stripper plate 61. The shell 21 is thus left standing on the stripper plate 61, free of the core 54, and may be removed from the machine.

After the shell 21 has been formed on the frame 23 by any method, such as the one above described, the lining 22 may be inserted through the door opening and it may be secured to the door jamb 28 as hereinbefore described. If the back of the cabinet is not made of molded material but is left open to receive a rear wall 34', as shown in Fig. 5, then the lining, if preferred, may be inserted through the back of the cabinet. When inserted through the back of the cabinet, the lining, if desired, may have the insulation attached to said lining before insertion into the cabinet, or, if desired, the method of forcing the insulation into the space by pumping means as heretofore described may be used.

The lower rectangular band 27 may have its horizontal flanges 70 made to extend only to the inner edge of the shell 21 in order that the core 54 may be inserted into the cabinet. If a bottom is desired in the cabinet, a plate 71 may be secured to the lower rectangular band 27 by any suitable means and gliders 72 may comprise part of the fastening means of the plate 71. If desired, however, separate gliding means may be provided.

While I have shown plungers 57 and 58 as horizontally reciprocable against the core 54, other door forming means may be used, if desired.

For instance, cores of the thickness of the shell 21, and of the shape of the door opening may be removably attached to the core 54. Upon downward movement of the core 54, these door cores being attached to the core 54, are carried downwardly with the core 54. The door cores may be detached from the core 54 before the cabinet is stripped from the core 54, but after it has been removed from the mold 53.

The cabinet, if it is to be used for mechanical refrigeration, may have a cooling unit generally designated as 80, placed therein. If the cooling unit is of the evaporator type, it may comprise a float chamber 81 receiving liquid refrigerant through pipe 82 and discharging evaporated refrigerant through pipe 83, the admission of liquid refrigerant being controlled by a float valve (not shown) in chamber 81 connected to pipe 82. Depending from chamber 81 may be provided cooling coils 84 surrounding ice tray sleeves 85. The front of the cooling unit 80 may be enclosed by a shield 86 having openings 87 connected to sleeves 85 for receiving ice trays. A drip pan 88 provided with opening 89 and bonnet 90 may be placed beneath the cooling unit, and may be supported by struts 91 suitably mounted on the lining. Racks 92 for receptacles and food to be cooled may be provided. The cooling unit may be suspended from the lining by straps 93. The pipes 82 and 83 may be connected to a refrigerating mechanism located in the compartment 94 or outside the refrigerator.

While the form of embodiment of the present invention as herein disclosed constitutes a preferred form, it is to be understood that other forms might be adopted, all coming within the scope of the claims which follow.

What is claimed is as follows:

1. A refrigerator cabinet comprising an outer shell member of molded composition material having great structural strength, said outer shell member having rectangular skeleton metal structural framework comprising horizontal and vertical members joined together concealed and embedded within said outer shell member, said outer shell forming the outer finished portion of the cabinet as well as the main structural member of the cabinet, an opening in the outer shell for a door opening, an insulating member extending around the door opening and securely fastened to the outer shell, an inner liner just slightly smaller than the door opening in the outer shell and the insulating member so that the inner liner is slidable into and out of the door opening, the front edges of the inner liner being securely fastened to the insulating member, a finishing member extending around the door opening and covering the front edges of the inner liner and door opening and insulation between the inner liner and the outer shell.

2. A refrigerator cabinet comprising an outer shell member of molded composition material having great structural strength, said outer shell forming the outer finished portion of the cabinet including all of the outer upright walls, and forming the main structural member of the cabinet, an opening in the outer shell for a door opening, an inner one piece liner just slightly smaller than the door opening in the outer shell so that the inner one piece liner is slidable into and out of the door opening, an insulating member connecting the front edges of the inner liner with the outer shell at the door opening.

WILLIAM C. HOLBROOK.
